CONTAINER CLOSURE

Frederick A. Vastano, Glen Rock, N. J., and Karl Erickson, Millbury, and Robert R. St. Jean, Auburn, Mass., assignors, by direct and mesne assignments, of one-half to Alfred W. Vibber, Ridgewood, N. J., and one-half to said Vastano

Application May 24, 1949, Serial No. 95,088

6 Claims. (Cl. 215—40)

1

This invention relates to a removable and replaceable container closure such as a bottle cap.

The container closure of the present invention represents a further development and an improvement over the container closure disclosed and claimed in application Serial No. 71,980, and now Patent No. 2,600,086, filed January 21, 1949, by Frederick A. Vastano, and entitled "Container Closure." Although the replaceable container closure shown and claimed in application Serial No. 71,980 is satisfactory in that it is rugged, fairly cheaply made, and rather easily manipulated, it possesses a disadvantage in that it adds appreciably to the height of the capped bottle. Furthermore, the cap of the previous application consists of six or seven parts, and, especially in that embodiment in which an adjustment as to height of the sealing disc is provided, such cap normally requires two hands to apply and to seal it.

In the container closure of the present invention the sealing member operating cam is enclosed completely within the main body of the closure. Consequently a great saving in the total height of the closure is effected, the closure of the invention being but little taller than the ordinary crown cap for bottles. A tall soda or ginger ale bottle provided with the cap of the invention may be stood upright in a modern refrigerator having but little clearance above the crown cap initially provided on such tall bottle. In the preferred embodiments of the closure of the invention the operating lever protrudes from one side of the main body thereof. As a result, the closure is more easily operated than is the above mentioned former closure, and may normally be applied to the bottle and brought into sealing relationship therewith by one hand. Furthermore, the closure of the invention, in preferred embodiments, is composed of fewer parts than is the former closure, the closure of the present invention being more readily adapted to having the main parts thereof formed in automatic machines.

It is, accordingly, an object of the invention to provide a container closure, such as a bottle cap, of the type above described which is short, simple, and rugged in construction, and which is easily applied to and removed from the container such as a bottle.

This and further objects of the invention will be more readily apparent in the following description of preferred embodiments thereof.

In the drawings accompanying the specification and forming a part thereof:

Fig. 1 is a view in side elevation of a first embodiment of the container closure of the invention affixed to the neck of a bottle;

Fig. 2 is a view in plan of such closure;

Fig. 3 is a view in vertical section through the

2

first embodiment of the closure and the neck of the bottle to which it is affixed, the section being taken along the line 3—3 in Fig. 1;

Fig. 4 is an enlarged fragmentary view in vertical section through the cap, the section being taken along the line 4—4 in Fig. 3; and

Fig. 5 is a view in vertical section, similar to Fig. 3, of a second embodiment of the container closure of the invention.

As above indicated, Figs. 1, 2, 3, and 4 of the drawing show a first preferred embodiment of the container closure of the invention, and Fig. 5 shows a second embodiment thereof. The first embodiment of the container closure, shown here as a cap for a bottle, such as a bottle containing soda water or ginger ale, is designated generally by the reference character 2. The main body 6 of the cap 2 is generally in the form of an inverted cup, as shown in Fig. 3. Cap 2 is applied to a bottle, of which the neck is shown at 4, by being slid sidewardly thereof, when the sealing means is in inoperative position, so that the inwardly extending bead engaging flange 12 engages the underside of the bead 10 at the top of the bottle. The flange 12 extends somewhat more than 180° around the cap, terminating at the ends 14 and 16 indicated in Figs. 1 and 2. The portion of the cap at the right in Fig. 1, containing flange 12, is in the form of a depending skirt 8, the portion of the cap at the left having such flange cutaway on the level A—A, as shown. Body 6 is provided on its outer surface with a knurled annular rib 3 adjacent the top thereof by which the cap is readily grasped and manipulated.

In the embodiment of the cap shown in Fig. 3, the main body 6 is preferably formed from bar stock on an automatic screw machine, the cavity within the main body having its sidewalls formed, after the main body has been hollowed out, by means of a form cutter. Such form cutter produces bottle bead receiving groove 13, the bead engaging flange 12, and, in this embodiment, the groove 18 bounded on the bottom by the second upper inwardly projecting flange 19, which is generally of the same inner diameter as the flange 12. The upper flange 19 lies above the line of cut A—A along which the skirt is removed on the left-hand side of the cap, as shown in Fig. 1. Positioned within the cavity in the main body 6 coaxially thereof is the imperforate sealing disc 20 made of resilient material, such as rubber and the like. Disc 20 is of a diameter greater than the inner diameter of flange 19 so that such disc is retained within the groove 18 by the flange 19. Disc 20 is, in this embodiment, of approximately the same diameter as the inner diameter of groove 18, and is approximately of the same thickness as the width of such groove, as shown. Lying above sealing disc 20 is the rigid plunger

forming disc 22 made of steel or the like, which constitutes the means for pressing disc 20 upon the upper surface of the bottle in sealing relation therewith. Disc 22 has a diameter no greater than, and preferably slightly smaller, as shown, than the inner diameter of the upper flange 19 and of the inner diameter of the main body 6 above groove 18.

In the embodiment shown, the sidewalls of the main body 6 of the cap are provided, immediately adjacent the upper inner surface 29 thereof, with two diametrically opposed radial openings 36 and 38 therethrough. Through such openings there extends the cam providing operating member generally designated 24. Member 24 is formed, in this instance, from spring wire stock, the central portion thereof within the cavity in the cap being deformed to provide the offset cam providing portion 26 which lies in a vertical plane, as the cap is depicted in Fig. 3. On both sides of the offset portion 26 member 24 is provided with straight portions, that at 28 extending on its outer end through the opening 36 and being headed at 32, and that at 30, at the right of portion 26, as shown in Fig. 3, extending through the opening 38 in the sidewall of the main body of the cap. Outwardly of opening 38 member 24 is bent into the form of an operating arm 34, extending, in this instance, at right angles to the portions 28 and 30 of member 24 and lying in the same plane which contains the offset portion 26.

In the embodiment shown in Fig. 3, wherein holes 36 and 38 lie immediately adjacent the surface 29 of the main body 6, the portions 28 and 30 of member 24 are supported by contact with surface 29 when cam forming member 26 presses disc 22 and sealing member 20 downwardly into sealing engagement with the top of the bottle-neck. Because member 22 in this embodiment is formed of spring wire, there is sufficient resilience in the offset portion 26 so that such resilience, taken in combination with the resilience of sealing member 20, effects and maintains over long periods a tight sealing engagement between disc 20 and the upper surface of the bottle neck when member 24 is turned into the operative sealing position of member 24 shown in Fig. 3.

Member 24 is stably held in such sealing position by means of the flattened portion 36' at the bottom of offset 26, more clearly shown in Fig. 4. It will be obvious that when member 24 is turned so that offset 26 lies vertical, as shown in Figs. 3 and 4, member 24 will be stably held in such sealing position by reason of the engagement of the flattened surface 36' on the offset and the upper flat surface of member 22. There is shown in dotted lines in Fig. 4 the position which offset 26 assumes when handle 34 is turned to horizontal inoperative position. It will be apparent that member 24 may be turned in either direction from the sealing position shown in Fig. 4 to relieve the sealing member from the bottle neck so that the cap may be removed therefrom.

In the first described embodiment of the cap the sealing member 20 is preferably not attached to the disc 22. The parts of the cap are assembled as follows: The main body of the cap, formed as above described, is provided with the two diametrically opposed openings 36 and 38 through the sidewall thereof. Opening 38 is preferably slightly larger than opening 36. The member 24, formed with the offset 26 and with the handle 34 bent, as shown, is then inserted with its end 28 first through the opening 38 and

65

70

75

then through the opening 36. Thereupon the forward end of portion 28 of member 24 is headed, as shown at 32, to retain such member in the main body of the cap. The plunger forming disc 22 is then inserted within the cavity of the main body, such insertion being possible due to the smaller diameter of member 22 relative to the flanges 12 and 19. The sealing member 20 is then inserted, the outer edge of such member snapping past the upper flange 19 and into groove 18 to retain member 22 in position within the main body of the cap at all times. Member 20 is deformed, as shown, somewhat by means of its engagement with flange 19 when members 28 and 22 are advanced by cam 26 into sealing relationship with the bottle neck. When handle 34 is turned to a horizontal position, member 20, by reason of its engagement with flange 19, causes plunger 22 to follow somewhat the cam providing offset 26, thereby retracting it from the upper surface of the bottle neck and allowing the ready retraction of the cap from the neck by sliding the cap laterally of the latter.

The bottle cap of the second embodiment, shown in Fig. 5, is similar in its main elements to that above described. Those portions of the structure shown in Fig. 5 which are the same as those shown in Figs. 1 to 4, inclusive, are designated by the same reference characters primed. In the structure of Fig. 5 the main body 6' of the cap differs from the body 6 in that there is but one flange on the inner surface of the sidewall thereof, such flange being the bead engaging flange 12'. The parts are similarly formed and, with the exception of sealing disc 20' are of the same relative dimensions as those in the first described embodiment. The parts of the cap shown in Fig. 5 are assembled in the same manner as are those of Figs. 1 to 4, inclusive. In the embodiment of Fig. 5, however, sealing disc 20' is made of a diameter somewhat exceeding the inner diameter of body 6' above flange 12', so that it firmly engages the inner sidewalls of the portion 6' of the cap above flange 12', as shown. Such engagement is sufficient to retain plunger member 22', which may be adhered to member 20' as by means of an interposed layer of bonding cement 21, in the upper portion of the cavity of the cap. Consequently, the sealing unit composed of elements 20' and 22' remains within the upper part of the cap body and does not drop when handle 34' is swung horizontally to relieve member 20' of sealing engagement with the bottle cap. The plunger and sealing member also remain in assembled relationship with the body of the cap when the cap is removed from the bottle.

Although for purposes of illustration we have shown and described two preferred embodiments of the container closure of the invention, it is to be understood that such closure is capable of numerous variations as to details. The invention is, therefore, defined by the scope of the claims appended hereto.

We claim as new the following:

1. A cap for a bottle having a neck, an opening at the top of the neck, and a bead encircling the neck, comprising a main body in the form of an inverted cup having a portion adapted to overlie the upper end of the bottle neck, a depending skirt on the main body extending throughout at least slightly more than 180° around the neck, the skirt having an inwardly directed bead engaging flange thereon, the termini of the skirt being spaced sufficiently to

allow the cap to be slid onto the bottle neck, said main body having a substantially flat inner upper surface lying normal to the vertical axis of the main body, a plunger in the form of a rigid disc mounted within the main body coaxially thereof for reciprocation toward and away from the opening in the bottle, sealing means in the form of a resilient disc spanning the hollow in the main body and the opening in the bottle and lying parallel to and generally in contact with the lower surface of the rigid disc, the edge of the resilient disc having frictional contact with the sidewall portion of the main body, a pair of diametrically opposed radial openings in the sidewalls of the main body immediately adjacent and substantially tangential to the margins of the inner upper surface of the main body, a wire member extending through said openings, said wire member having an offset portion lying in a plane and forming a cam cooperating with the rigid disc member generally centrally thereof, the portions of the wire member on each side of the offset portion being straight and lying in contact with the upper inner surface of the main body, one end of the wire member outwardly of the sidewall of the main body being bent to lie in the plane of the offset and generally at a right angle to the main extent of the wire member within the main body, the outer surface of the offset portion of the wire member being flat and lying at a right angle to the plane containing the offset, the rigid disc being free of connection to either the cap main body or the cam and being loosely retained between the cam and the resilient disc.

2. A cap for a bottle having a neck, an opening at the top of the neck, and a bead encircling the neck, comprising a main body in the form of an inverted cup having a portion adapted to overlie the upper end of the bottle neck, a depending skirt on the main body extending throughout at least slightly more than 180° around the neck, the skirt having an inwardly directed flange thereon, the termini of the skirt being spaced sufficiently to allow the cap to be slid onto the bottle neck, said main body having a substantially flat inner upper surface lying normal to the vertical axis of the main body, a plunger in the form of a rigid disc mounted within the main body coaxially thereof for reciprocation toward and away from the opening in the bottle, sealing means in the form of a resilient disc spanning the opening in the bottle lying parallel to and generally in contact with the lower surface of the rigid disc, a pair of diametrically opposed radial openings in the sidewalls of the main body adjacent the inner upper surface of the main body, a wire member extending through said openings, said wire member having an offset portion lying in a plane and forming a cam cooperating with the rigid disc member generally centrally thereof, the portions of the wire member on each side of the offset portion being straight and lying in contact with the upper inner surface of the main body, one end of the wire member outwardly of the sidewall of the main body being bent to lie in the plane of the offset and generally at a right angle to the extent of the wire member within the main body, the outer surface of the offset portion of the wire member being flat and lying at a right angle to the plane containing the offset, said rigid disc having a diameter substantially no greater than the inner diameter of the bead engaging flange, said resilient disc having a relaxed diameter greater than the inner diameter of the main body above the bead engaging flange, whereby the periphery of the resilient disc frictionally engages the inner wall of the main body, the rigid disc being free of connection to either the cap main body or the cam and being loosely retained between the cam and the resilient disc.

above the upper lip of the bottle when the cap is placed on the bottle, said upper flange having an inner diameter generally the same as that of the lower, bead engaging, flange, said rigid disc having a diameter no greater than the inner diameter of the second flange, said resilient disc having a diameter greater than the inner diameter of the second flange, the periphery of the resilient disc lying above the second flange on the body of the cap, the rigid disc being free of connection to either the cap main body or the cam and being loosely retained between the cam and the resilient disc.

3. A cap for a bottle having a neck, an opening at the top of the neck, and a bead encircling the neck, comprising a main body in the form of an inverted cup having a portion adapted to overlie the upper end of the bottle neck, a depending skirt on the main body extending throughout at least slightly more than 180° around the neck, the skirt having an inwardly directed flange thereon adapted to engage the underside of the bead on the bottle neck, the termini of the skirt being spaced sufficiently to allow the cap to be slid onto the bottle neck, said main body having a substantially flat inner upper surface lying normal to the vertical axis of the main body, a plunger in the form of a rigid disc mounted within the main body coaxially thereof for reciprocation toward and away from the opening in the bottle, sealing means in the form of a resilient disc spanning the opening in the bottle and lying parallel to and generally in contact with the lower surface of the rigid disc, the edge of the resilient disc having frictional contact with the sidewall portion of the main body, a pair of diametrically opposed radial openings in the sidewalls of the main body immediately adjacent and tangential to the margins of the inner upper surface of the main body, a wire member extending through said openings, said wire member having an offset portion lying in a plane and forming a cam cooperating with the rigid disc member generally centrally thereof, the portions of the wire member on each side of the offset portion being straight and lying in contact with the upper inner surface of the main body, one end of the wire member outwardly of the sidewall of the main body being bent to lie in the plane of the offset and generally at a right angle to the extent of the wire member within the main body, the outer surface of the offset portion of the wire member being flat and lying at a right angle to the plane containing the offset, said rigid disc having a diameter substantially no greater than the inner diameter of the bead engaging flange, said resilient disc having a relaxed diameter greater than the inner diameter of the main body above the bead engaging flange, whereby the periphery of the resilient disc frictionally engages the inner wall of the main body, the rigid disc being free of connection to either the cap main body or the cam and being loosely retained between the cam and the resilient disc.

4. A cap for a bottle having a neck, an opening at the top of the neck, and a bead encircling the neck, comprising a main body in the form of an inverted cup having a portion adapted to overlie the upper end of the bottle neck, a depending skirt on the main body extending throughout at least slightly more than 180° around the neck, the skirt having an inwardly directed flange thereon adapted to engage the underside of the bead on the bottle neck, the termini of the skirt being spaced sufficiently to allow the cap to be slid onto the bottle neck, said main body having

a substantially flat inner upper surface lying normal to the vertical axis of the main body, a plunger in the form of a rigid disc mounted within the main body coaxially thereof for reciprocation toward and away from the opening in the bottle, sealing means in the form of a resilient disc spanning the opening in the bottle and lying parallel to and generally in contact with the lower surface of the rigid disc, the edge of the resilient disc having frictional contact with the side wall portion of the main body, a pair of diametrically opposed radial openings in the sidewalls of the main body immediately adjacent and tangential to the margins of the inner upper surface of the main body, a wire member extending through said openings, said wire member having an offset portion lying in a plane and forming a cam cooperating with the rigid disc member generally centrally thereof, the portions of the wire member on each side of the offset portion being straight and lying in contact with the upper inner surface of the main body, one end of the wire member outwardly of the sidewall of the main body being bent to lie generally at a right angle to the extent of the wire member within the main body, said rigid disc having a diameter substantially no greater than the inner diameter of the bead engaging flange, said resilient disc having a relaxed diameter greater than the inner diameter of the main body above the bead engaging flange, whereby the periphery of the resilient disc frictionally engages the inner wall of the main body, the rigid disc being free of connection to either the cap main body or the cam and being loosely retained between the cam and the resilient disc.

5. A cap for a bottle having a neck, an opening at the top of the neck, and a bead encircling the neck, comprising a main body in the form of an inverted cup having a portion adapted to overlie the upper end of the bottle neck, a depending skirt on the main body extending throughout at least slightly more than 180° around the neck, the skirt having an inwardly directed bead engaging flange thereon, the termini of the skirt being spaced sufficiently to allow the cap to be slid onto the bottle neck, said main body having a substantially flat inner upper surface lying normal to the vertical axis of the main body, a plunger in the form of a rigid disc mounted within the main body coaxially thereof for reciprocation toward and away from the opening in the bottle, sealing means in the form of a resilient disc spanning the hollow in the main body and the opening in the bottle and lying parallel to and generally in contact with the lower surface of the rigid disc, the edge of the resilient disc having frictional contact with the sidewall portion of the main body, a pair of diametrically opposed radial openings in the sidewalls of the main body immediately adjacent and substantially tangential to the margins of the inner upper surface of the main body, a wire member extending through said openings, said wire member having an offset portion lying in a plane and forming a cam cooperating with the rigid disc member generally centrally thereof, the portions of the wire member on each side of the offset portion being straight and lying in contact with the upper inner surface of the main body, one end of the wire member outwardly of the sidewall of the main body being bent to lie generally at a right angle to the main extent of the wire member within the main body, the rigid disc being free of connection to either the cap main body or the cam

and being loosely retained between the cam and the resilient disc.

6. A cap for a bottle having a neck, an opening at the top of the neck, and a bead encircling the neck, comprising a main body in the form of an inverted cup having a portion adapted to overlie the upper end of the bottle neck, a depending skirt on the main body extending throughout at least slightly more than 180° around the neck, the skirt having an inwardly directed bead engaging flange thereon, the termini of the skirt being spaced sufficiently to allow the cap to be slid onto the bottle neck, said main body having a substantially flat inner upper surface lying normal to the vertical axis of the main body, a plunger in the form of a rigid disc mounted within the main body coaxially thereof for reciprocation toward and away from the opening in the bottle, sealing means in the form of a resilient disc spanning the opening in the bottle lying parallel to and generally in contact with the lower surface of the rigid disc, a pair of diametrically opposed radial openings in the sidewalls of the main body adjacent the inner upper surface of the main body, a wire member extending through said openings, said wire member having an offset portion lying in a plane and forming a cam cooperating with the rigid disc member generally centrally thereof, the portions of the wire member on each side of the offset portion being straight and lying in contact with the upper inner surface of the main body, one end of the wire member outwardly of the sidewall of the main body being bent to lie at a right angle to the extent of the wire member within the main body, said main body having a second inwardly directed flange thereon above the lower, bead engaging, flange, the upper flange lying above the upper lip of the bottle when the cap is placed on the bottle, said upper flange having an inner diameter generally the same as that of the lower, bead engaging, flange, said rigid disc having a diameter no greater than the inner diameter of the second flange, said resilient disc having a diameter greater than the inner diameter of the second flange, the periphery of the resilient disc lying above the second flange on the body of the cap, the rigid disc being free of connection to either the cap main body or the cam and being loosely retained between the cam and the resilient disc.
